UNITED STATES PATENT OFFICE

CLARENCE P. HULST, OF TALBOT COUNTY, MARYLAND

DRIP PAN

Application filed January 10, 1933. Serial No. 651,049.

My invention consists in a new and useful improvement in drip pans, and is designed more particularly to provide a pan for use with the carburetor float chamber of an outboard motor. During years of almost daily use of outboard motors for seven months of each year, and having owned five different types and sizes of motors, I have found that the most annoying feature of this kind of motor is the spilling of mixed gasoline and lubricating oil from the carburetor float chamber, every time the motor is tilted. In motors of this character, as is well known, the lubricating oil must be supplied with the fuel, through the carburetor, with the inevitable result that any discharge from the float chamber has in it this lubricating oil, and while the gasoline which is spilt evaporates, the oil remains, so that the oily mess has to be wiped off of the stern seat and out of the bilge continually. Otherwise the after part of the boat is no fit place to be, unless one wears working clothes. With most outboard motors, tilting is necessary in re-fueling, and is always necessary in clearing the propeller from weeds or sea grass. It is always done when the boat is beached, and frequently in driving the boat over shoals and bars. At night, most motors being too unwieldy and heavy to be easily removed from the boat, they are tilted so that the propeller and underwater gear-housing clear the water. On each and all of these occasions, the mixed gasoline and oil remaining in the carburetor float chamber when the motor is stopped drain out into the boat and eventually into the bilges. My improved drip pan entirely obviates this very disagreeable feature of the outboard motor.

By the use of my improved device, all mixed gasoline and oil which is in the carburetor float chamber, when the motor is stopped, drains out into a small receptacle attached to the float chamber, and flows over the side through a flexible tube when the motor is tilted back into running position. Also, any overflow, from flooding of the float chamber while the engine is running, is caught in the receptacle and drains over the side. When my device has been installed, the rear seat and bilges will be kept entirely free from gasoline and oil, and the whole after part of the boat will be clean enough to be occupied by a driver in white duck clothing. The device weighs but a few ounces, can

be made to fit any carburetor float chamber, and can be installed quickly and easily by any one. Since it has no moving parts to wear, it will last indefinitely.

While I have illustrated in the drawings filed herewith and have hereinafter fully described one specific embodiment of my invention, it is to be distinctly understood that I do not consider my invention limited to said specific embodiment, but refer for its scope to the claims appended hereto.

In the drawings:

Fig. 1 is a side elevation of an outboard motor, in inoperative position, with my improved pan applied to the carburetor float chamber.

Fig. 2 is a similar view, showing the motor in operative position.

Fig. 3 is a vertical section of my pan, the outer portion of the clamping ring being shown in elevation.

Fig. 4 is an horizontal section on line 4-4 of Fig. 3.

Fig. 5 is a view similar to Fig. 4, the clamping ring being reversed to allow the device to be applied to a float chamber upon the right side of the carburetor.

Fig. 6 is a bottom plan view of the device illustrated in Fig. 4.

Fig. 7 is a view similar to Fig. 4, illustrating a modified form of my device designed for application to a float chamber upon the left side of the carburetor.

Fig. 8 is a bottom plan view of the device illustrated in Fig. 7.

Fig. 9 is a bottom plan view of the modified form of my device designed for application to a float chamber upon the right side of the carburetor.

In the drawings:

The outboard motor M is pivoted to the clamp C applied to the transom of the boat, by the pintle pin P, and has the carburetor float chamber F on the carburetor R, and the fuel tank T with fuel line L to the carburetor R, having the petcock S. My improved drip pan D may be made of any suitable material and fabricated by any suitable method so as to have the two walls 1 and 2 at an angle of substantially 90° to each other, with the V-shaped top end 3, forming a trough, and the bottom pentagonal end 4, with the extension walls 5 and the lip 6, forming a cup at right angles to the trough.

As can be observed from Figs. 1 and 2,

the parts of my improved pan D are so designed that the pan D will fit about the float chamber F, the walls 1 and 2 embracing the cylindrical chamber F and the extension walls 5 and lip 6 fitting below the chamber F.

In order to adjust the pan D to the chamber F, I provide an arcuate spring collar 7 having two tapped bolts 8 passing through the walls 1 and 2 respectively and fastened 10 by nuts 9 with washers 10 to obviate leakage. It is obvious, from Figs. 4 and 5, that these parts are so designed that the collar 7 is reversible, so as to provide means for attaching the pan D upon a float chamber F 15 upon either side of the motor M.

To the bottom end 4, I attach a spout 11, a hole 12 being provided in the bottom 4 to communicate with the interior of the spout 11, and to this spout 11, I attach a suitable drain 20 pipe 13 which may be suitably supported by a guide 14 attached to the motor M.

In Figs. 7, 8 and 9, I have illustrated a modified form of my improved pan D, the article being made to fit a particular float chamber F. In this form, since the pan D is intended to be used upon only one type of float chamber F, the spout 11—a is deflected toward either the right or left side, according to whether the float chamber F is upon the 30 right or left side of the motor M, and the attaching collar 7—a is permanently attached to the walls 1 and 2 by rivets 15. In this form, also, the collar 7—a may be dispensed with, and the pan D attached to the float chamber F by means of tapped bolts.

From the foregoing description of the details of construction of my improved pan D, its use will be obvious. When the motor M is moved into inoperative position, as illustrated 40 in Fig. 1, for any reason, the tipping of the float chamber F will cause escape of gasoline and oil. This is necessary, since it is impossible to seal the chamber F. It is obvious from Fig. 1 that my improved pan D is so disposed, when the motor M is tipped, as to catch any gasoline and oil escaping from the chamber F in the trough formed by the walls 1 and 2. When the motor M is again moved into operative position, as illustrated 45 in Fig. 2, it is obvious that the escaped liquid, trapped in the cup of pan D, flows out through the spout 11 and pipe 13 over the side.

Having described my invention, what I 55 claim is:

1. In a drip pan for the float chamber of the carburetor of an outboard motor, the combination of a trough having one of its ends fitted over the top of said chamber; and a cup formed at the other end of said trough and fitted below said chamber.

2. In a drip pan for the float chamber of the carburetor of an outboard motor, the

combination of a trough having one of its ends fitted over the top of said chamber; a cup formed at the other end of said trough and fitted below said chamber; and a spout for said cup.

70

3. In a drip pan for the float chamber of the carburetor of an outboard motor, the combination of a container having one of its ends fitted over the top of said chamber and its other end fitted below said chamber; a pipe from said container; and attaching means on said motor to position the discharge end of said pipe over the side.

75

4. In a drip pan for attachment to the float chamber of the carburetor of an outboard motor, the combination of a trough; and a cup formed at the end of the trough and forming a continuation of the trough, the parts being so related that liquid escaping from the float chamber when it is tilted will be retained in the trough, and will drain through the cup when the chamber is restored to its normal position.

80

5. In a drip pan for attachment to the float chamber of the carburetor of an outboard motor, the combination of a trough; a cup formed at the end of the trough and forming a continuation of the trough; and a discharge pipe from said cup, the parts being so related that liquid escaping from the float chamber when it is tilted will be retained in the trough, and will drain through the cup and pipe when the chamber is restored to its normal position.

95

6. In a drip pan for the float chamber of the carburetor of an outboard motor, the combination of a trough; a pair of walls extending from the top of said trough at one of its ends; a lip connecting said walls over a portion of said trough to form a cup; and a spout adjacent said lip in the end of the trough to drain fuel collected in the trough.

100

7. In a drip pan for the float chamber of the carburetor of an outboard motor, the combination of a trough with a cover over a portion of its length to form a cup adapted to receive fuel collected in the trough when the motor is tilted; and a spout for said cup adapted when the motor is returned to normal position to drain the fuel from the cup.

110

8. In a drip pan for the float chamber of the carburetor of an outboard motor, the combination of a trough with a cover over a portion of its length to form a cup adapted to receive fuel collected in the trough when the motor is tilted; a spout for said cup adapted when the motor is returned to normal position to drain the fuel from the cup; and means on said trough for attachment to the chamber.
